FIG. 4 is a front elevational view of the article carrier of FIG. 3.

U.S. PATENT DOCUMENTS

The portions of FIGS. 1–4 shown in broken lines are for illustrative purposes only and form no part of the claimed design. The boundary of the bowtie shaped panel is defined by the solid line and the dot-dash lines. The dot-dash lines define a boundary such that the bowtie shaped panel extends to the boundary but does not include the boundary.
